RADIATOR CORE

Fred M. Opitz, Milwaukee, Wis., assignor to
Hexcel Radiator Company, Milwaukee, Wis., a
corporation of Wisconsin

Application February 25, 1935, Serial No. 7,957

15 Claims. (Cl. 257—130)

The present invention relates to radiators, and is particularly concerned with the provision of a new and improved radiator core of the fin and tube type.

A further object of the present invention is the provision of a radiator core of great strength and durability, and which possesses strong resistance to twisting and weaving stresses. In this connection, a further object of the present invention lies in the provision of a radiator core in which not only are the tubes freed completely from structural loads but, in addition, the tubes are so constructed that a free flow of water at all times occurs and the tubes are such as are not damaged when subjected to freezing pressures. More specifically, it is an object of the present invention to provide a radiator core of the fin and tube type in which the fins, although individually connected with the tubes, are arranged to be interlocked together in self-sustaining relation so that, although they are secured to the tubes, the fins are not carried by the tubes.

A still further object of the present invention is to provide a radiator having all of the advantages of radiators of the honeycomb and cellular type as to their thermal capacity, but which, at the same time, does not possess the disadvantages of such radiators as regards their tendency to become clogged and the tendency for soldered seams to open under freezing and mechanical stresses, especially those involved in the use of the radiator on moving vehicles and the like which are subjected to considerable vibration. More specifically, it is an object of the present invention to provide a radiator of the fin and tube type in which the thermal efficiency of the radiator is not reduced by excessive amounts of solder or other relatively poor heat conducting metal.

An additional object of the present invention is the provision of a radiator core of the fin and tube type in which the marginal sections of the tubes are so constructed and arranged as to be highly resistant to damage by surface crushing and bending and which, at the same time, affords a general appearance somewhat like a radiator of the honeycomb or cellular type. Ordinary radiators of the fin and tube type have fins which are easily bent upon being struck by even relatively light objects or light blows, and when bent such fins materially interfere with the flow of air through the radiator, thus appreciably reducing the efficiency of the unit.

These and other objects and advantages of the present invention will be apparent from the following description of the preferred structural

embodiment, illustrated in the accompanying drawings.

In the drawings:

Figure 1 is a perspective view of one of the fins with sections broken away at different portions; 5

Figure 2 is a plan view of the fin shown in Figure 1;

Figures 3, 4, and 5 are transverse sections taken, respectively, along the lines 3—3, 4—4, and 5—5 of Figure 2 and looking in the direction of 10 the arrows;

Figures 6 and 7 are longitudinal sections taken, respectively, along the lines 6—6 and 7—7 of Figure 2;

Figure 8 is a front view of a portion of a completed radiator core with portions broken away 15 along a central section;

Figure 9 is a sectional view of two fins, taken along the line 9—9 of Figure 2, illustrating how the fins are all formed alike and showing their 20 uniformity of shape;

Figure 10 illustrates the relation between adjacent fins when alternate ones have been reversed end for end in the process of assembling the fins to form a radiator core, Figure 10 showing the manner in which the crests of the corrugations carry interlocking means to receive complementary interlocking means carried by the fins intermediate the corrugated portions thereof; 25

Figure 11 is a perspective, including sections taken generally along the line 11—11 of Figure 12 showing a modified form of strip; 30

Figure 12 is a plan view of the strip or fin shown in Figure 11;

Figure 13 is a section taken along the line 35 13—13 of Figure 12 looking in the direction of the arrows;

Figure 14 is a section taken along the line 14—14 of Figure 12;

Figures 15, 16, and 17 are longitudinal sections taken, respectively, along the lines 15—15, 16—16, 40 and 17—17 of Figure 12;

Figure 18 is a section corresponding to Figure 16 and showing two adjacent fins after one has been reversed end for end and ready to be mechanically interlocked together but before the 45 water tubes have been inserted;

Figure 19 is a face view, with portions broken away along a central plane and illustrating a portion of the completed radiator core; 50

Figure 20 is a section taken along the line 20—20 of Figure 19 and illustrating in particular the manner in which the fins of the radiator core are interlocked together; and

Figures 21 and 22 are sections taken along the 55

lines 21-21 and 22-22, respectively, of Figure 20.

Referring now to the drawings, more particularly to Figures 1 to 10, it will be seen that 5 radiator core constructed according to the principles of the present invention embodies a plurality of water tubes 1 and interlocked fins 2 of generally corrugated formation having crests 5 separated by intermediate portions 6. The 10 marginal portions of the fins are also corrugated at opposite edges thereof, as at 8 and 9, preferably having a pitch α equal to the pitch of the central corrugations 5. As best shown in Figures 1 and 2, the central corrugations 5 are of truncated 15 pyramidal formation, the marginal corrugations 8 and 9 being in the form of half truncated pyramids. The sections 5, 8 and 9 are all in the form of protuberances extending from the same side of the general plane of the strip of metal forming the fin, the metal being thereby drawn or stretched in the formation of the central and marginal corrugations or protuberances. This stretching of the metal is an important element 20 of the present invention in that the active area of metal by which heat from the water tubes is 25 radiated or dissipated is increased, according to the principles set forth in my prior Patent No. 1,706,584, issued March 26, 1929.

Each of the central corrugations or protuberances 5 include oppositely sloping walls 5a and 5b and end walls 5c, the end walls 5a sloping laterally in opposite directions from the crest of the protuberance 5, as best shown in Figure 3. The half corrugations 8 and 9 along the marginal sections of the strip or fin 2 have crests 12, flattened for purposes which will appear later, and bottom portions 13 opposite the intermediate portions 6 of the central series of corrugations or protuberances 5. In order to avoid stressing the 30 metal of the strip excessively the marginal corrugations 8 and 9 also have laterally inner walls 15 sloping toward the end walls 5c of the central corrugations. As best shown in Figures 1, 2, and 3, portions of the strip, indicated by the reference 35 numeral 16, are extended from the sloping wall of the marginal corrugation to the adjacent sloping end wall of the central corrugation in order to relieve the strip of any excessive or localized 40 stresses at this point in the formation of the central and marginal corrugations and their contiguously disposed sloping walls 5c and 15. The ridges 16 also provide for a somewhat greater 45 air passageway through the core, as will be apparent from Figure 8. Between the flattened crests 12 of the marginal corrugations 8 and 9 are intermediate flattened or corrugated sections 18 which, as will be explained later, reinforce the face of the radiator core against crushing and deformation. Reinforcing the face and 50 back of the core materially improves the construction because, if any of the air passageways are obstructed, the efficiency of the radiator is to that extent reduced, and corrugating the marginal sections in this manner, providing a number 55 of angularly disposed sections, serves to secure materially greater strength of this portion of the radiator fin against being crumpled or crushed.

The core being of the fin and tube type, the 60 fins must have suitable openings to receive and contact with the water tubes of the radiator core. According to the principles of the present invention, I provide the central portion of the fin with a series of tube receiving openings formed by first 65 slitting and then piercing the fins in the manner

set forth in my prior patent mentioned above. Preferably, each of the central protuberances contains three tube receiving openings, 21, 22, and 23, the opening 21 being formed in the sloping wall 5a and the other two openings 22 and 23 being spaced apart laterally a distance slightly less than the length of the opening 21, as shown in Figures 3 and 4, and formed partly in the other sloping wall 5b with the laterally outer end portions of the openings 22 and 23 extending in the 10 sloping end walls 5c. By virtue of this construction I have provided a row of tube receiving openings 21 in the center of the strip or fin and two rows of openings 22 and 23 disposed generally in the central portion of the strip but spaced apart 15 as best shown in Figure 2, there being two openings on one side of the crest of each protuberance 5 and one opening on the other side. The distance longitudinally of the fin between the opening 21 and the adjacent two openings 22 and 23 20 of each protuberance 5 is substantially the same as the distance between the two openings 22 and 23 of one protuberance and the opening 21 of the next protuberance.

Each of the tube receiving openings 21, 22, and 25 23 are formed, as mentioned above, by piercing, and this is for the purpose of leaving inwardly extending flanges around the opening, as best shown in Figure 1 in which the flanges around the various openings are indicated, respectively, 30 by the reference numerals 21a, 22a, and 23a. By virtue of these flanges, a good contact between the fin and the tubes is had since the flanges are slightly resilient and will engage the tubes irrespective of any slight inaccuracies in the actual 35 size of the tube receiving openings.

According to the principles of the present invention, means is provided whereby, when the several radiator fins are assembled in making the complete core, the fins form a self-sustaining 40 assembly so that, even though they are not rigidly secured to the tubes but merely in contact therewith, the core unit as a whole is mechanically complete and rigid. By making the unit thus self-sustaining, the water carrying tubes are not 45 called upon to support the fins and are therefore free to perform their own function of conducting the cooling medium. Moreover, the several fins or strips are mechanically interlocked together not only to secure and preserve their self-sustaining 50 characteristic but, in addition, to facilitate the assembly of the core and the assembly of the water tubes and the several fins. However, even though the fins are corrugated and provided with means, which will be presently described, 55 whereby the fins are mechanically interlocked, yet according to the principles of the present invention the several fins each have individual contact with the tubes and are therefore exceptionally efficacious in dissipating heat from the 60 tubes.

Referring now for the moment to Figure 9, it will be seen that I have shown two fins or radiator strips as they come from the strip forming machine with the corrugations and tube receiving openings and flanges in nested relation, except that they are spaced apart in order to show the relations involved. In forming the radiator, the strips are severed at one end at the intermediate portion between the corrugations 5 and, at the other end, at the crest of the corrugation. Next, alternate strips are reversed or turned end to end, so as to bring the crests of one strip into registry with the intermediate or valley portions of the other strip, as best shown in Fig- 75

ure 10. As will at once be apparent, by virtue of this arrangement, the adjacent tubes are in contact at spaced points with the other portions of the strips separated and can then serve as air passageways between the strips. Now in order to mechanically interlock the strips when alternate ones are reversed end for end, as just referred to, I provide an additional series of pierced openings, one to receive the other when the strips or fins are assembled in the relation shown in Figure 10.

Referring now to Figure 1 again, the interlocking means comprises flanged and pierced openings 30 and 31 formed in the center of the strip and spaced longitudinally, the openings 30 being formed in the section of the fin intermediate the truncated pyramidal protuberances 5 or corrugations 5, and the openings 31 are formed at the crests of said corrugations or protuberances. In general, the openings 30 and 31 are similar to the tube receiving openings 21, 22, and 23 described above, with the exception that the interlocking openings 30 and 31 are not as wide. However, the openings 30 and 31 each are pierced so as to provide interlocking flanges 30a and 31a. As best indicated in Figures 9 and 10, the openings 31 in the crests of the corrugations or protuberances 5 are wider than the openings 30 formed in the intermediate sections of the fin between the protuberances of corrugations 5. This arrangement is for the purpose of permitting the flanges 30a of the intermediate interlocking openings 30 to be telescopically received in the openings 31 of the crests and between the flanges 31a thereof, as best indicated in Figures 8 and 10, when the strips are reversed end to end in the relation shown in those figures. By virtue of this construction, then, the mere reversal and bringing together of alternate strips automatically secures all of the strips or fins in a mechanically interlocked and self-sustaining relation. The openings 31 receive the flanges 30a of the intermediate openings so that once the strips are brought to the position shown in Figure 10, the strips or fins cannot get out of position either laterally or longitudinally with respect to each other.

After the desired number of fins have been assembled in mechanically interlocked relation as set forth above, they are placed in a jig, all of the water tube receiving openings being in alignment and held in alignment by virtue of the mechanical interconnection between the fins. The fins or strips are then compressed to bring the radiator core to the desired dimension, and then the water tubes are inserted in the openings. Any suitable means may be used for placing the water tubes in position. For example, they may be inserted by hand since, by virtue of the pierced type of tube receiving openings and the flanges of the openings, it is a relatively simple matter to push each tube in position. For this purpose, if desired, I may use a tool 35 best shown in Figure 8 having a reduced end 36 and a shoulder 37. The reduced end fits on the inside of a tube and the shoulder engages the end thereof so that the tube may be quickly and easily shoved through the core openings into proper position.

The tubes 1 may be of any convenient construction, but preferably they are of the double seam type, formed of copper or any other suitable material, and they have their exterior surface tinned before they are inserted in the strips or

fins. After all of the water tubes have been placed in position, end plates 40 (Figure 8) having suitable openings punched therein to receive the tube ends, are disposed over the fins. The end strips or plates 40 are flat, and, like the fins 2 described above, also have pierced openings 41 with flanges 41a. After the end plates, tubes and fins have been placed in position, the jig is then removed and the core baked or heated to approximately 450° F. This is sufficient to melt the tin on the tubes, and subsequent cooling secures the end plates and the fins to the tubes themselves. After this is done, the front and rear faces of the core, that is, the marginal fin portions 8 and 9, are dipped in a thin bath of solder for the purpose of securing the contacting portions of the marginal corrugations of the fins together. It is to be noted that solder is not applied to the tubes themselves but only to the edges of the fins. Solder is not a good conductor of heat, and a radiator in which the entire core is dipped is a relatively inefficient unit. After the core is thus completed, upper and lower water tanks may be secured in any manner desired, as by soldering or the like, to the upper and lower plates 40. Figure 8 shows a portion of the completed radiator, and it will be noted that the generally diamond or hexagonally shaped opening formed by the marginal portions of the strips or fins 2 serve as air passageways for leading the air in between adjacent water tubes 1. The tubes themselves are spaced closer together than the width of the air passageway so that the tubes have a Venturi-like effect when air is drawn through the core for the purpose of securing a lateral flow of air in addition to the flow of air directly through the core induced by the fan or whatever other means is provided for causing air to flow through the radiator.

As will be apparent from Figures 2 and 8, the spacing of the water tubes longitudinally of the fins is equal to one-half the pitch a of the fin corrugations. It will also be noted that by virtue of the auxiliary marginal corrugations 18, the appearance of the radiator core resembles the appearance of a cellular radiator of the honeycomb type, but what is more important, the marginal portions of the fins are strengthened by these auxiliary corrugations, and the radiator core is materially reenforced against damage by crushing or bending of the faces or marginal edges of the fins.

The principles of the present invention, especially in their broader aspects, can be embodied in radiator cores of a different formation than the construction described above. For example, in Figures 11 to 20 a somewhat simpler form of radiator core is shown, one which embodies practically all of the features mentioned above, especially those having to do with the mechanical interlocking of the plurality of fins, the separate and individual contacts between the fins and the water tubes, and the attachment of the fins to the several tubes.

Referring now more particularly to Figure 11 which shows one of the fins used in the modified radiator core, it will be observed that, like the construction described above, the fin is comprised of a strip of metal having a series of central and marginal corrugations, the central corrugations being indicated by the reference numeral 50 and the marginal corrugations being indicated by the reference numerals 51 and 52.

Like the corrugations described above, the central corrugations of the strip shown in Figure 11 are in the nature of truncated pyramidal protuberances disposed laterally along the strip or fin, all being disposed to one side of the general plane of the strip. Likewise, the marginal corrugations 51 and 52, like the marginal fin corrugations 8 and 9 described above, are in general similar in formation to truncated pyramidal 10 projections, with crests 55 disposed on the same side of the general plane of the strip as the protuberances, and with valleys 56 or intermediate portions disposed on the other side of the general plane on the strip. These corrugations 15 or protuberances are formed preferably by drawing or stretching the metal of the strip from which the fin is made. As described above, this is for the purpose of increasing the active area of the fins as compared with the original area of the strip before manufacture. Moreover, to reduce the localization of stresses during this drawing or stretching operation, portions of the strip 20 between the marginal corrugations 51 and 52 and the central corrugations or protuberances are extended, as at 58.

As best indicated in Figures 11 and 12, each of the central protuberances or corrugations 50 have oppositely sloping side walls 60 and 61 and oppositely sloping end walls 62 and 63, and the 30 sloping side and end walls terminate upwardly in a flattened crest section 64. The pitch of the central protuberances or corrugations 50 is equal to twice that of the marginal corrugations 51 and 52, as best shown in Figures 12 and 15 to 17.

As in the modification previously described, the fin shown in Figures 11 and 12 is provided with the plurality of water tube receiving openings 67 in the central portion of the strip. The openings 67, as best shown in Figure 12, are disposed in the sloping side walls 60 and 61 on either side of the flattened crest 64 of each protuberance substantially midway between crest 64 and the adjacent valley, indicated by the reference numeral 69. At each side of the central 40 series of openings 67 are openings arranged in two series 70 and 71, the former being formed in the end walls 63 and in the intermediate valley portions 69 of the strip, and the openings 71 are formed in the opposite end walls 62 and 50 in the portions of the valley sections 69 between the protuberances 50. The openings 70 and 71 are in transverse alignment and, as best shown in Figure 12, are staggered with respect to the series of openings 67.

Each of the tube receiving openings 67, 70, and 71 are formed in the strip by piercing, rather than punching, so that flanges 70a and 70b are provided around the openings, as best indicated in Figures 11 and 15 to 17, and, where the openings 60 70 are elongated, as in the present construction, the end flanges 70b are usually in the nature of pointed projections, but it is to be understood that according to the present invention the proportions or dimensions of the flanges is not of particular consequence. Similarly, the openings 67 and 71 are provided with side and end flanges 67a, 67b and 71a, 71b.

As in the modification described above, all of the strips are identical so far as their corrugations or protuberances are concerned, and after the strips have been formed into fins of the type best shown in Figure 11, they are severed at one end at a valley portion 69 and at the other end at a crest portion 64. Then the strips are assembled with alternate ones reversed so that the

strips occupy the relative positions shown in Figure 18 with the valley portion 69 of one strip in engagement with the crest portions 64 of the next lower strip. By virtue of this arrangement, when the fins are assembled they are mechanically interlocked together, as best indicated in Figures 18 to 20. Referring for the moment to Figure 18, it will be noted that the strips indicated are not quite in engagement, but that the end flanges or points 70b at the valley portions 69 of the upper fin are adapted to register with the end flanges 71b at the crest of the lower fin. Figure 20 shows the fins in completely nested relation.

The distance between the end flanges 70b and 71b in the valley portion 69 of one fin is slightly 15 in excess of the distance between the end flanges 70b and 71b in the crest portion of the next lowest fin, as best illustrated in Figure 20, so that when the strips are assembled these end flanges on the valley portions 69 of the fin embrace the corresponding flanges on the adjacent crest section 64. Also, at each side the immediate inner portions of the side flanges 70a at one side interlock with the side flanges 71a of the next fin, as best shown in Figure 20. Each set of interlocking flanges 20 will serve to prevent any displacement of one fin with respect to the other, either longitudinally or laterally, so that all that is required to hold all of the assembled fins in position is to keep them from separating so as to retain the flanges in 25 interlocking relation. As best shown in Figure 19, when the flanges are thus employed to secure the fins in interlocked relation, the marginal corrugations 51 and 52 are in engagement, the valley sections 56 from one fin engaging the crest sections 55 of the adjacent fin. Figure 19 also includes a sectional view which further illustrates the manner in which the flanges interlock. In fact, these flanges are telescoped in much the same manner as set forth in my prior patent referred to above, particularly when the water tubes 30 are in place.

The water tubes are indicated by the reference numeral 90, and these are inserted in the tube receiving openings 67, 70 and 71 after the fins have 45 been assembled and interlocked together. The presence of the tubes in the openings 70 and 71, whose side flanges and inner end flanges are in interlocked telescoping relation as described and as illustrated in Figures 21 and 22, serve to maintain the interlocked relation because of the friction between the tubes and the openings and flanges with which the tubes are in engagement. The metal from which the fins is formed possesses some resiliency and since the tube receiving openings are pierced, the flanges all extend in the same direction when the fins are severed. This facilitates the insertion of all of the tubes from one direction, the flanges frictionally gripping the tube after it has been inserted to prevent its removal. Also, since the flanges 70b and 71b are telescoped at their inner portions the tubes hold the fins in frictional contact. While, also, the inner portions of the side flanges 70a and 71a are in telescoping relation, the resiliency of the strips 55 is such that at their outer portions, where the flanges 70a and 71a are spaced apart vertically, each has individual contact with the tubes, as indicated in Figures 20, 21, and 22.

Referring now more particularly to Figure 19, it 70 will be observed that the pitch of the marginal corrugations is only one-half of the pitch of the central corrugations or protuberances 50, and it will also be observed that the marginal corrugations 55—56 are displaced one-quarter of their 75

pitch out of transverse alignment with the central corrugations or protuberances 50. By virtue of this arrangement, when alternate fins are reversed end for end, with the water tube receiving openings in alignment and with the end and side flanges thereof mechanically interlocked as explained above, the crests 55 of each fin will engage the valley portion 56 of the adjacent fins. Thus, when the fins are properly assembled and the tubes inserted, the marginal corrugations 51 and 52 form the pattern of the radiator.

The marginal corrugations of Figure 19 are only one-half the pitch of the central corrugations and they need not have the intermediate crimps described above in connection with the previous modification, since the face of the radiator core having these relatively fine pitch marginal corrugations offers sufficient resistance to crushing and bending. Of course, the marginal sections 51 and 52 could, if desired, be provided with such intermediate crimps similar to those indicated at 18 in the previously described modification. Also, the pitch of the marginal corrugations 51 and 52 could be doubled, particularly when provided with such crimps, in which case they need not be displaced out of transverse alignment with the central corrugations, but could be, as described in the previous modification, in alignment therewith.

30 Fins are arranged to provide for air passageways between the tubes, and to this end the intermediate crimps 58 referred to above serve to somewhat enlarge these air passageways while, at the same time, the tubes act as Venturi-like 35 restrictions to provide for variations in the velocity of air through the radiator in order to promote lateral circulation.

Both of the modifications described above are assembled in practically the same manner. As 40 mentioned above, the individual fins as they come from the fin forming machine are cut at a valley portion at one end and at a crest portion at the other end, and then the group of fins are assembled with alternate ones reversed. That is, 45 the first fin will be laid with the crest-severed end at the left, for example, and then the next fin will be laid oppositely, that is, with its crest-severed end at the right. The next fin will then be laid with its crest-severed end to the left, and 50 the next will be laid with its crest-severed end to the right and so on. As the core is thus built up to the required size, each fin as it is laid is mechanically interlocked with the next lower fin by virtue of the interengaging flanges 70a, 55 70b, 71a, and 71b. The core end plates 95 are assembled with the fins, that is, the bottom end plate is laid first, then the fins are assembled as indicated above, and finally when the core has been completed, the upper or top plate is laid.

60 After the radiator core has been formed to the desired size, the assembled fins are placed in a jig and compressed slightly to the proper size. This compression is relatively slight and is easily accommodated by the resiliency of the fins. 65 While it is held in a jig, the water tubes are inserted from the upper end, that is, from the upper end of the core where the flanges are extended downwardly. The curvature of the metal immediately surrounding the tube receiving openings serve to guide the tubes and facilitate their insertion in the aligned or registering tube receiving openings. This can be done relatively rapidly, and in order to facilitate their insertion, the tool 35 described above is connected with

the first modification and can be used in assembling either the first or second modification.

After all of the tubes have been inserted, the fins grip the tubes with rather firm frictional contact due to the multiplicity of points of contact and also due to the resiliency of the flanges. After thus being assembled, then, the jig can be removed and the radiator core will retain the dimensions given to it by the jig itself. The tubes used, according to the principles of the present invention are of the double-lock seam type, but it is to be understood that the seamless tubes may be used if desired.

Preferably, according to the principles of the present invention, the tubes before insertion in the fins have been tinned, and then after the core has been assembled and the tubes inserted, the core is baked or heated to a point above the melting point of tin for a short period of time, so that when the core is removed and cools, the tin sets and secures each fin to all of the tubes, that is, each of the side and end flanges are, in effect, permanently fastened to the tube in intimate and firm contact without the use of solder or without dipping the core itself.

This is a very important advantage of the present invention. First, solder is a relatively heavy substance, and, second, its heat conductivity is relatively low so that a radiator dipped in solder is heavy and inefficient thermally. I avoid these disadvantages by securing each fin to each of the tubes in the above manner, and in both modifications each fin is secured to each tube in spaced relation with respect to the other fins. This is literally true in the case of the first modification and, for all practical purposes is true for the second modification, the only difference being that, as indicated in Figures 20, 21, and 22, portions of the inner sections of the side flanges and end flanges of the openings 70 and 71 are 30 mechanically telescoped a short distance. However, as best shown in Figures 20 and 22, the major portion of the side flanges 70a and 71a are 35 in individual contact with the associated water tubes.

45 After the radiator core has thus been baked and cooled to set the tin, and thus secure the fins to the tubes, the front and back faces of the radiator core are dipped in a thin bath of solder just sufficient to secure the contacting portion 50 of the marginal corrugations together 51 and 52. Also, the top and bottom plates of the radiator core are dipped in a bath of solder to rigidly fasten the plates to the ends of the tubes.

While I have shown and described above the 55 preferred structure in which the principles of the present invention have been embodied, it is to be understood that my invention is not to be limited to the specific details shown and described above, but that, in fact, widely different means 60 may be employed in the practice of the broader aspects of my invention.

What I claim, therefore, and desire to secure by Letters Patent is:

1. A radiator fin comprising a strip of metal 65 having a series of spaced truncated pyramidal protuberances formed in the central portion of the strip, marginal corrugations along the edges of the strip, tube receiving openings formed in the sloping sides of said protuberances, and 70 other tube receiving openings in said strip spaced from said first tube receiving openings.

2. A plurality of fins having central corrugations of a given pitch and height, marginal corrugations having the same height as said central 75

corrugations and a pitch equal to one half of the pitch of said central corrugations, and tube receiving openings formed in the central corrugations on opposite sides thereof in symmetrical sets, the marginal corrugations being disposed out of registry with said central corrugations a distance equal to one quarter of the pitch of the latter, the disposition of said marginal corrugations being such that when one of said fins is 5 reversed end for end with respect to the other and the tube receiving openings are aligned, the high and low points, respectively, of each of said sets of corrugations are in engagement, said tube receiving openings being arranged to be in registry with the tube receiving openings in the other fins both before and after reversal of alternate fins.

3. A radiator fin comprising a strip of metal having a central series of protuberances extending 20 in the same direction from the plane of the strip, there being pairs of flanged tube receiving openings in the crests of said protuberances and in the spaces between the protuberances the distance between the adjacent ends of the openings 25 in the spaces between the protuberances being slightly different than the distance between the adjacent ends of the openings in the crests of said protuberances, whereby the portions of said flanges at said ends interlock in telescoping relation whenever the strips are assembled with 30 said openings in alignment and with the crests of the protuberances of one strip registering with the intermediate spaces between the protuberances of the adjacent strip.

35 4. A plurality of identical radiator fins, each comprising a series of centrally disposed corrugations having tube receiving openings spaced on either side of the crests thereof, a series of marginal corrugations, said central corrugations being disposed all at one side of the original plane of the strip and the marginal corrugations being disposed first to one side and then to the other side of said plane, the pitch of the marginal corrugations and their disposition relative to said tube receiving openings being such that, when the fins are assembled with alternate ones reversed end to end, corresponding tube receiving openings are in alignment and the crests of the central and marginal corrugations of each strip 50 meet, respectively, the intermediate portions between the crests of the central and marginal corrugations of the adjacent strip.

55 5. A plurality of identical radiator fins, each comprising a strip of metal having a series of spaced truncated pyramidal protuberances formed in the central portion of the strip, corrugated marginal portions at the edges of the strip, a set of flanged openings at the sides of the crests of said protuberances, and a second set of flanged 60 openings disposed in the strip between said protuberances, portions of the flanges of one set of openings cooperating with the other set of openings, when the strips are assembled with alternate strips reversed end for end, to interlock all of said strips and hold them against relative displacement, the corrugations of said marginal portions being spaced longitudinally of the fin with respect to the central protuberances and said 65 flanged openings thereof, so that when alternate strips are reversed end for end and said flanged openings interlocked the marginal portions form a connected protecting pattern.

70 6. A radiator core comprising a plurality of fins and tubes, said fins having portions with

flanged openings receiving said tubes and arranged at an angle to one another, so that at one point the flanges of adjacent openings overlap, whereby the fins are mechanically interlocked together and at other points the flanges 5 are spaced apart and have separate contact with the tubes.

7. A radiator core of the fin and tube type comprising a plurality of fins having sets of tube receiving openings with portions mechanically interlocked together, the other portions of the fins being spaced apart and provided with other sets of tube receiving openings therein, tubes disposed in said interlocked tube receiving openings, and other tubes disposed in said spaced openings. 10 15

8. A radiator core comprising a plurality of corrugated fins having central portions mechanically interlocked together and marginal portions also corrugated with parts of the marginal corrugations of one strip in engagement with and secured to parts of the marginal portions of the adjacent strips to form the external pattern of the core there being tube receiving openings on opposite sides of the mechanically interlocked portions in the central section of the fins, and water tubes disposed in said openings, said fins being out of contact with one another between said marginal corrugations and the central interlocked portions of the fins. 20 25

9. A radiator core of the fin and tube type comprising a plurality of fins formed of strip material, each fin having portions offset in opposite directions from the general plane of the strip and said fins being assembled with certain portions of adjacent strips in direct contact and other portions of said strips spaced apart a distance equal to twice the distance between the general planes of said strips, means at the portions of said strips in direct contact for mechanically interlocking adjacent fins together, aligned 30 tube receiving openings in the fins separate from said interlocking means and intermediate the portions of the adjacent strips in direct contact and the portions thereof spaced farthest apart, and tubes disposed in said openings and contacting 35 said fins. 40 45

10. A radiator core of the fin and tube type comprising a plurality of water tubes and fins having central and marginal corrugations of equal pitch, each of the central corrugations 50 having a plurality of openings to receive said tubes and said fins being assembled with their corrugations in contact to form cellular passageways for the flow of air therethrough and around the tubes, the corrugations of the marginal portions being crimped between the crest and invert portions thereof in a direction transversely of the core so as to strengthen the face of the core against damage. 55

11. A radiator core of the fin and tube type 60 comprising a plurality of water tubes and corrugated fins having openings to receive said tubes, the central corrugations of the fin having a pitch twice that of the corrugations in the marginal sections of the fins, said fins being assembled with their corrugations in contact to form cellular passageways for the flow of air through the tubes, and the tubes being spaced in the core a distance substantially equal to the 65 pitch of said marginal corrugations. 70

12. A radiator fin comprising a strip of metal having a series of spaced truncated pyramidal protuberances formed in the central portion of the strip, a plurality of rows of tube receiving 75

openings formed in the fin, each of the openings of one row lying wholly in the sloping sides of said protuberances between the crest and bottom of each and the tube receiving openings of 5 at least one other row extending into the sloping end portions of said truncated pyramidal protuberances.

13. A radiator fin comprising a strip of metal having a central series of protuberances extending in the same direction from the plane of the strip, there being flanged tube receiving openings lying wholly in the sides of the crests of said protuberances, and aligning flanges spaced longitudinally of the strip from said tube receiving 10 openings and disposed in the crests of the protuberances.

14. A radiator fin comprising a strip of metal having a central series of protuberances of generally pyramidal formation, there being tube receiving openings in the sloping sides and ends of each of the protuberances, and a series of marginal corrugations formed in opposite edges of the strip and displaced from points in transverse alignment with said protuberances a dis- 15

tance substantially equal to one-fourth the pitch of the marginal corrugations.

15. A radiator core comprising a plurality of identical radiator fins, each consisting of a strip having a series of spaced truncated pyramidal protuberances formed in the central portion thereof and separate marginal corrugations disposed longitudinally of the strip out of transverse alignment with respect to the central protuberances, there being tube receiving openings 10 in the sloping sides and ends of the protuberances and in the spaces between the latter, the marginal corrugations being disposed longitudinally of the strip out of transverse alignment with the tube openings a distance equal to a fraction of 15 their pitch, whereby when alternate fins are reversed end for end and the tube openings in adjacent strips aligned so that the inner ends of the openings in the intermediate portions of the strips engage the inner ends of the opening in 20 the crests, the marginal corrugations of adjacent strips are brought together to form a connected protecting pattern.

FRED M. OPITZ.
